UNITED STATES PATENT OFFICE.

FREDERICK E. MANNING, OF LOS ANGELES, CALIFORNIA.

FUEL-HEATER.

1,117,414.

Specification of Letters Patent. Patented Nov. 17, 1914.

Application filed May 25, 1914. Serial No. 840,837.

To all whom it may concern:

Be it known that I, FREDERICK E. MANNING, a citizen of the United States, residing at the city of Los Angeles, in the county 5 of Los Angeles and State of California, have invented new and useful Improvements in Fuel-Heaters for Internal-Combustion Engines, of which the following is a specification.

10 My invention relates to that class of internal combustion engines in which hydrocarbons of high specific gravity, such as distillate is used as fuel.

It is a well known fact that hydrocarbons 15 of high specific gravity such as distillate when used as fuel for internal combustion engines require to be heated to a considerably higher temperature than fuels of low specific gravity such as gasoline in order 20 to be properly ignited and exploded in the cylinders and that great difficulty has been heretofore experienced in utilizing such fuel owing to the inability of properly heating such fuel.

25 It is the object of my invention to provide means to obviate the above noted objections, which will be cheap and simple in construction and which can be easily and quickly positioned for use upon an explosion engine without materially altering the same.

Another object is to provide means whereby the temperature of the fuel may be regulated as desired.

35 A further object is to provide a heating means for the above purpose which can be operated without any additional cost other than the initial cost of installation.

I accomplish these objects by the mechanism described herein and illustrated in the accompanying drawings forming a part hereof in which:

40 Figure 1 is a side elevation, partly in section, of the intake and exhaust manifolds and carbureter of an internal combustion engine with my device attached thereto. Fig. 2 is a perspective view of the deflector. Fig. 3 is a perspective view of a modified form of deflector.

45 In the drawings 5 is the exhaust pipe, 6 the intake manifold and 7 the carbureter of an internal combustion engine of any approved construction. In the exhaust pipe 5 at any convenient point is provided a threaded port 8 into which is screwed a deflector 9 which deflector extends partly in-

side and partly outside of the exhaust pipe 5. Deflector 9, as best shown in Fig. 2, is preferably formed of an ordinary pipe nipple of suitable diameter and length which 60 has a portion of one end cut away at the side thereof leaving a projecting or deflecting portion or wing 10 extending into the exhaust pipe 5. An ordinary pipe L 11 is screwed onto the end of the deflector which 65 projects outside of the exhaust pipe and has its other end connected to one end of a flexible pipe or tube 12 the other end of which is connected to one end of the vaporizing tube 13. Vaporizing tube 13 is 70 preferably a piece of brass tubing of sufficient length to extend longitudinally through the intake manifold 6 centrally thereof, and projects a short distance outwardly from each end. The outer projecting end of tube 13 is in threaded connection with the intake manifold at 14 and is provided with a pipe L 15. Pipe L 15 is provided with an outlet pipe 16 which extends downwardly to any convenient point. 75 The inner projecting end of tube 13 is passed through a bushing 17 which bushing is in threaded connection with manifold 6, to its connection with the end of flexible tube 12. A butterfly or other valve 18 is provided within tube 12 to partially open or close the passage therethrough and is operated by means of a flexible wire 19 which wire extends to a suitable connection at a 80 convenient point of operation.

85 In operation with the parts in the position shown in the drawings the exhaust gases as they pass through exhaust pipe 5 will have a part thereof deflected by deflector 9 into and through tube 12, through vaporizing tube 13 and thence through pipe 16 to atmosphere. As the exhaust gases pass through vaporizing tube 13 said tube will be heated thereby and the fuel which is drawn from the carbureter by the suction of the engine will impinge upon or strike against said tube and will be vaporized or heated. Valve 18 is opened or closed to regulate the flow of the exhaust gases through tube 13 thereby supplying a 90 greater or less amount of heat as required.

95 While I have shown and described my preferred form of construction it will be understood that I do not limit myself to such construction.

100 Fig. 3 shows a modified form of deflector. Having described my invention what I

claim as new and desire to obtain by Letters Patent is.

1. A fuel heater for internal combustion engines comprising a deflector secured to the exhaust pipe of the engine, said deflector extending partly within and partly without the said exhaust pipe; a tube extending longitudinally and centrally through the intake manifold between the carbureter and the cylinders; having one end thereof open to atmosphere; a connection between said deflector and the other end of said tube.

2. A fuel heater for internal combustion engines comprising a deflector secured to the exhaust pipe of the engine, said de-

flector extending partly within and partly without the said exhaust pipe; a tube extending longitudinally and centrally through the intake manifold between the carbureter and the cylinders; having one end thereof open to atmosphere; a connection between said deflector and the other end of said tube; and means to regulate the passage of exhaust gases through said tube.

In witness that I claim the foregoing I have hereunto subscribed my name this 20th day of May, 1914.

FREDERICK E. MANNING.
